UNITED STATES PATENT OFFICE.

CARL J. FORSBERG, OF PLAINFIELD, NEW JERSEY, ASSIGNOR TO NILESBEMENT-POND COMPANY, OF JERSEY CITY, NEW JERSEY.

TURRET-LATHE.

No. 821,351.

Specification of Letters Patent.

Patented May 22, 1906.

Application filed March 30, 1904. Serial No. 200,839.

To all whom it may concern:

Be it known that I, CARL J. FORSBERG, a citizen of the United States, residing at Plainfield, Union county, New Jersey, have invented certain new and useful Improvements in Turret-Lathes, of which the following is a specification.

This invention, pertaining to improvements in turret-lathes and relating to mechanism for turning and arresting the turret, will be readily understood from the following description, taken in connection with the accompanying drawings, in which—

Figure 1 is a plan of the turret-slide and its immediate accessories, partly appearing in horizontal section in the plane of line *b* of Fig. 2; Fig. 2, a vertical longitudinal section of the same in the plane of line *a* of Fig. 1; Fig. 3, a rear elevation of the turret, the bed appearing in vertical transverse section; Fig. 4, a vertical longitudinal section of the turret-slide and its immediate accessories in the plane of line *c* of Fig. 1 in conjunction with the adjustable block which operates the turret-releasing and turret-turning mechanism; Fig. 5, an end elevation of the tail end of the bed, showing the turret-turning mechanism; Fig. 6, a plan of the same; Fig. 7, a diagram of the turret-turning mechanism, and Fig. 8 a rear elevation of the adjustable block.

In this machine, the turret-slide with its turret slides on the bed, impelled in any usual manner and by any usual means. The turret is turned automatically on its slide when moved to a certain point toward the tail end of the bed, and the feeding motion is automatically arrested when the turret is moved to selected distance toward the head-stock. Where features of construction are not particularly shown or described they may be assumed to be as usual in this class of machines.

In the drawings, 1 indicates the lathe-bed; 2, the turret-slide sliding thereon; 3, the turret turning on the turret-slide and illustrated as being arranged for the reception of six turret-tools; 4, the usual arm supported by the bed between the turret-slide and head-stock and designed when the turret-slide reaches it to effect the arrest of the further advance of the turret toward the head-stock. The arm 4 has a moderate motion and is connected with any suitable device for interrupt-

ing the feed of the slide. After moving sufficiently upon contact by one of the stop-rods 8 (as hereinafter described) to stop the feed of the slide the arm 4 may be arranged to "bring up solid" and act as a positive fixed stop, definitely arresting motion of the slide and turret at a determined point.

5 represents a volute cam fast with and turning with the turret, being disposed upon the lower portion of the turret structure below the top of the slide; 6, a transverse guideway carried by the turret-slide; 7, a carriage moving on this guideway and capable of adjustment thereon transverse to the width of the lathe; 8, a series of long stop-rods mounted for endwise adjustment in the carriage 7, their ends toward the head-stock being adapted selectively to come into contact with the stop-arm 4, there being one of these stop-rods for each of the turret-tools; 9, set-screws in the carriage 7 for holding the stop-rods therein in adjusted endwise relationship to the carriage; 10, a lever pivoted within the turret-slide and having one end coupled to the stop-rod carriage 7 and the other end provided with a roller engaging the cam 5; 11, a spring urging the roller of the lever toward the cam.

The relation of the cam and the stop-rods is to be such that at the use of each tool of the turret an appropriate one of the stop-rods will be in line with arm 4 and impinge upon that arm. The turning of the turret to bring a given turret-tool into active position therefore automatically brings the appropriate one of the stop-rods into active position. The stop-rods may be adjusted longitudinally to suit the desired degree of feeding advance desired for the particular turret-tool to which that stop-rod is appropriated. Therefore when the turret advances the stop-rod appropriated to the turret-tool in action will come into contact with the arm 4, resulting in the arrest of the feeding motion.

Proceeding with the drawings, 12 indicates the usual spring-bolt for locking the turret in adjusted angular position; 13, clamping-rings for clamping the turret firmly down to the turret-slide; 14, a rock-arm pivoted in the turret-slide and having connection with the spring-bolt and clamping-rings and serving when rocked to the right to loosen the clamping-rings and then withdraw the spring-bolt and permit the turret to be turned; 15, a

roller on a rock-arm rocking with arm 14; 16, another roller on a rock-arm rocking with arm 14, roller 16 being to the rear of roller 15 and the two being in different transverse planes; 5 17, a block longitudinally adjustable along the lathe-bed between the turret-slide and the tail end of the bed; 18, an incline carried by this block in the path of roller 15 as the turret-slide moves to the right; 19, a second incline tail- 10 wardly beyond incline 18 and similarly in the path of roller 15; 20, a cam carried by the block intermediate of the inclines 18 and 19 and in the path of roller 16, and 21 the longitudinal T-shaped slot in the lathe-bed in 15 which is adjusted and fixed the block 17.

Referring to Fig. 4, the turret is to be assumed as being in working condition locked by the spring-bolt and firmly clamped by the clamp-rings. When the turret is to be turned 20 to bring a new tool to position for use, the turret-slide is moved to the right, so the rollers can reach the block. Roller 15 first engages incline 18, with the result that arm 14 is rocked far enough to the right to loosen 25 the clamp-rings. The continued tailward motion of the turret-slide causes roller 15 to ride up incline 19 and cause the further rocking of arm 14 and the withdrawal of the spring-bolt, the turret being then at liberty 30 to be turned. The movement of the rock-arms as produced by the inclines has resulted in the swinging of roller 16 downwardly and to the left. The turret having been turned to desired position and the turret-slide started 35 to the left, roller 16 rides over cam 20, whereby the rock-arms are restored to normal position, resulting in the engaging of the spring-bolt and the tightening up of the clamp-rings. Particulars regarding the clamping 40 rings 13 may be found in United States Letters Patent No. 736,792, of August 18, 1903.

Proceeding with the drawings, 22 indicates a worm-gear fast with the turret; 23, a worm mounted in the turret-slide and engaging 45 this gear; 24, a worm-shaft splined in the worm and journaled at the tail end of the lathe; 25, a power-shaft journaled on the bed and adapted to have continuous rotary motion imparted to it by any appropriate 50 means; 26, a gear loose on the power-shaft; 27, a friction-clutch by means of which gear 26 may be locked to the power-shaft; 28, a lever for engaging and releasing the friction-clutch; 29, a gear fast on the worm-shaft in 55 the plane of gear 26; 30, an idle gear connecting gears 26 and 29, the result of the arrangement thus far described being that when the turret is unclamped and unlocked and the friction-clutch thrown into engagement the 60 turning of the power-shaft brings about the turning of the turret; 31, a gear mounted for free rotation, the illustration showing this gear as being mounted on the end of the worm-shaft; 32, a gear mounted for loose ro- 65 tation; 33, a pinion fast with gear 32 and en-

gaging gear 31; 34, a pinion fast with gear 29 and engaging gear 32; 35, a notch carried by gear 31, the illustration showing this notch as being formed in an annular flange projecting from the outer face of gear 31, and 36 a tooth carried by the clutch-lever 28 and adapted to enter notch 35 when the lever is in position corresponding with the released condition of the friction-clutch, the tooth when in the notch serving to arrest the forward rotation of gear 31.

The proportion of the gearing between the power-shaft and the worm-shaft is immaterial; but the proportion of the gearing between the turret and gear 31 is to be such 80 that gear 31 will make one turn for each division of the turret—that is to say, if the turret is arranged for six tools then gear 31 is to make six turns for each turn of the turret. The tooth of the clutch-lever occupies its 85 notch when the turret is in a working angular position and the friction-clutch is released. If the clutch-lever be thrown outwardly, the result is, first, that the tooth becomes released from its notch, thus leaving 90 the worm-shaft free to be turned, and, second, that the friction-clutch is engaged, thus setting the power-shaft to work in turning the turret. The lever having been moved outwardly and the clutch thrown into engagement, gear 31 starts in its rotation, and thereafter the unnotched portion of the gear prevents the release of the clutch until the gear shall have again brought the notch to the tooth. This rotation of the turret under 95 the influence of the power-shaft will continue so long as the clutch-lever is in outward position and will cease when the lever is again put to clutch-releasing position, which can only be done when the notch comes opposite 100 the tooth, this occurring each time the turning of the turret brings a turret-tool to working position. If the clutch-lever be thrown inwardly, the result is the disengagement of 105 the clutch and the accurate locking of the worm-shaft in position corresponding with some operative position of the turret.

As thus far described we may assume a hand operation of certain parts. Suppose the turret to be unclamped and unlocked 115 that it be desired to turn the turret one division. The clutch-lever may be thrown outwardly, thus releasing the tooth from the notch and at the same time engaging the clutch, whereupon the power-shaft proceeds to turn the turret. If now inward pressure be exerted upon the clutch-lever, such pressure will be ineffective until the notch reaches the tooth; but at that time the tooth will enter the notch and the clutch will be released 125 and the motion of the turret arrested accurately in its new angular position. Such effect may be produced regardless of the position of the turret-slide along the bed; but by mechanism to be later described provision 130

is made by which the turret-turning operation is automatically installed and arrested when the turret-slide is moved tailward upon the bed, so as to reach block 17.

Proceeding with the drawings, 37 indicates a tailwardly-presenting finger carried by the turret-slide; 38, a spring-plunger carried by block 17 in the path of finger 37; 39, the plunger-spring urging the plunger toward the turret-slide; 40, a pin sliding in block 17 parallel with the plunger; 41, a pin projecting laterally from the plunger in position to engage the inner end of pin 40; 42, a lever pivoted to block 17 and extending crosswise of the lathe-bed, the rear end of this lever being in the path of pin 40; 43, a link pivoted to and extending inwardly from the end of the clutch-lever; 44, a lever having one end connected with this link; 45, a rod pivoted to lever 44 and extending lengthwise of the lathe-bed and engaged adjustably by the forward end of lever 42; 46, a spring upon link 43, urging the clutch-lever to clutch-releasing position with its tooth to notch-engaging position; 47, a clamp device connecting the front end of lever 42 with rod 45 and permitting the lever to be connected with the rod in selective longitudinal position in accordance with the position in which block 17 is secured along the lathe-bed, and 48 a housing-plate for the support of the general mechanism at the tail end of the lathe-bed.

Normally the turret is locked and clamped and feeding to the left. When moved to the right, so as to be operated upon by block 17, the turret becomes unclamped and unlocked and free to be turned, as has been heretofore explained. A further movement of the turret-slide to the right causes finger 37 to engage the plunger and push it to the right, the spring of the plunger preventing shock as the turret-slide reaches its limit of motion. The rightward movement of the plunger results in the throwing of the clutch-lever to tooth-releasing and clutch-engaging position, whereupon the turret becomes turned by the power-shaft. The turret-slide having been started to the left leaves the clutch-lever quite free from its domination. The turning of the turret by power continues until gear 31 shall have made a full turn, whereupon spring 46 throws the tooth into its notch and releases the friction-clutch and arrests the further turning of the worm-shaft. The indexing effect of the tooth and notch upon the turret is so accurate as to almost render the locking-bolt dispensable.

I claim as my invention—

1. In a turret-lathe, the combination, substantially as set forth, with a bed, a turret-slide, a turret, and a feed-arresting arm, of a carriage mounted for sliding movement on the turret-slide in a direction transverse to the length of the bed, a series of stop-rods mounted in said carriage parallel with each other

and with the lathe-bed and adapted to coöperate selectively with the feed-arresting arm, and operative connections between the turret and said carriage to shift the carriage in accordance with the turning of the turret. 70

2. In a turret-lathe, the combination, substantially as set forth, with a bed, a turret-slide, a turret, and a feed-arresting arm, of a carriage mounted for sliding movement on the turret-slide in a direction transverse to the 75 length of the bed, a series of stop-rods mounted in said carriage parallel with each other and with the lathe-bed and adapted to coöperate selectively with the feed-arresting arm, a cam fast with the turret and a lever pivoted 80 on the turret-slide and having connections with said cam and carriage.

3. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 85 geared to turn in harmony with the turret and carrying a notch, a clutch-throwing member to serve in engaging and releasing the clutch, and a tooth upon the clutch-throwing member in position to enter said notch when opposite thereto and permit the clutch-throwing member to throw the clutch 90 to position of release.

4. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 100 geared to turn in harmony with the turret and carrying a moving plain surface provided with a notch, a clutch-throwing member to serve in engaging and releasing the clutch, and a tooth upon the clutch-throwing member in position to enter said notch when opposite thereto and permit the clutch-throwing member to throw the clutch to 105 position of release and adapted to bear against said plain surface when not opposite the notch.

5. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 115 geared to turn in harmony with the turret and carrying a notch, a clutch-throwing member to serve in engaging and releasing the clutch, a tooth upon the clutch-throwing member in position to enter said notch when opposite thereto and permit the clutch-throwing member to throw the clutch to 120 position of release, and a spring urging the clutch-throwing member to clutch-releasing position.

6. In a turret-lathe, the combination, sub- 130

stantially as set forth, with a bed, a turret-slide, a turret, a power-shaft, and transmitting mechanism between the power-shaft and the turret, of a friction-clutch interposed in said transmitting mechanism, a rotary member 5 geared to turn in harmony with the turret and carrying a notch, a clutch-throwing member to serve in engaging and releasing the clutch, and a tooth upon the clutch-throwing member in position to enter said notch when opposite thereto and permit the clutch-throwing member to throw the clutch to position of release.

7. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 15 geared to turn in harmony with the turret and carrying a notch, a clutch-throwing member to serve in engaging and releasing the clutch, a tooth upon the clutch-throwing member in position to enter said notch when opposite thereto and permit the clutch-throwing member to throw the clutch to position of release, a rod extending lengthwise of the bed and having connection with the clutch-throwing member, a tailwardly-presenting 20 projection carried by the turret-slide, mechanism connected with said rod and disposed in the path of said projection, and a spring urging the clutch-throwing member to clutch-releasing position.

8. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 25 geared to turn in harmony with the turret and carrying a notch, a clutch-throwing member to serve in engaging and releasing the clutch, a tooth upon the clutch-throwing member in position to enter said notch when opposite thereto and permit the clutch-throwing member to throw the clutch to position of release, a rod extending lengthwise of the bed and having connection with the clutch-throwing member, a tailwardly-presenting 30 projection carried by the turret-slide, a member disposed in the path of said projection near said rod, means for locking said last-mentioned member to selective longitudinal 35 positions upon said rod, and a spring urging the clutch-throwing member to clutch-releasing position.

9. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 40 geared to turn in harmony with the turret and carrying a notch, a clutch-throwing mem-

ber to serve in engaging and releasing the clutch, a tooth upon the clutch-throwing member in position to enter said notch when opposite thereto and permit the clutch-throwing member to throw the clutch to position 45 of release, a rod extending lengthwise of the bed and having connection with the clutch-throwing member, a tailwardly-presenting projection carried by the turret-slide, mechanism connected with said rod and disposed in the path of said projection, a spring urging the clutch-throwing member to clutch-releasing position, and a spring-buffer acting between the turret-slide and the bed and adapted to be compressed by the turret-slide 50 when the turret-slide moves tailwardly in the act of bringing said projection against said mechanism in its path.

10. In a turret-lathe, the combination, substantially as set forth, with a bed, a turret-slide, a turret, a power-shaft, and transmitting mechanism between the power-shaft and the turret, of a clutch interposed in said transmitting mechanism, a rotary member 55 geared to turn in harmony with the turret and carrying a notch, a clutch-throwing member to serve in engaging and releasing the clutch, a tooth upon the clutch-throwing member in position to enter said notch when opposite thereto and permit the clutch-throwing member to throw the clutch to position of release, a block adjustable lengthwise of the bed between its tail end and the turret-slide, a rod extending lengthwise of the bed and having connection with the clutch-throwing member, a movable member mounted on 60 said block and having connection with said rod at selective points along the length of the rod, a tailwardly-presenting projection carried by the turret-slide and adapted to engage the movable member on the block and shift the rod endwise, and a spring urging the clutch-throwing member to clutch-releasing position.

11. In a turret-lathe, the combination, substantially as set forth, with a bed, a turret-slide, a turret, a power-shaft, and transmitting-gears between the power-shaft and the turret, a clutch between the power-shaft and the turret, a gear turned by the power-shaft 65 in harmony with the turret and carrying a notch, a clutch-throwing lever to serve in engaging and releasing the clutch, and a tooth upon the clutch-throwing lever in position to enter said notch when opposite thereto and permit the clutch-throwing member to throw the clutch to position of release.

12. In a turret-lathe, the combination, substantially as set forth, with a bed, a turret-slide, a turret, a power-shaft for turning the 70 turret, and a train of transmitting-gearing between the power-shaft and the turret, of a clutch interposed between the power-shaft and the turret, a gear connected with said transmitting-gearing between the clutch and 75

- the turret and carrying a plain surface and a notch, a clutch-throwing lever, a spring urging said lever to clutch-releasing position, mechanism between the lever and the turret-
5 slide to cause extreme tailward movement of the turret-slide to throw the lever to clutch-engaging position, and a tooth upon the clutch-lever bearing upon said plain surface when the clutch is engaged and entering said 10 notch when opposite thereto and permitting the clutch to release.
13. The combination of a bed, a slide, a turret on said slide, power-driven means for revolving said turret, clutch means interposed in 15 said power-driven means, a revolute gear member impelled by said power-driven means and arranged to rotate once for a fractional part of the revolution of said turret, a clutch-throwing member, a tooth thereon, and a 20 notch on said revolute member adapted to be entered by said tooth.
14. The combination of a bed, a slide, a turret on said slide, power-driven means for revolving said turret, a clutch interposed in 25 said power-driven means, an intermittently-revolute member impelled by said power-driven means and having a definite speed of rotation with reference to that of said turret, a clutch-throwing member actuated by the 30 movement of said slide for engaging said clutch, means carried by said revolute member for engaging said clutch-throwing member and retaining said clutch in engagement for a determined period, and means for releasing said clutch.
15. The combination of a bed, a slide, a turret on said slide, power-driven means for revolving said turret, a clutch which may be engaged and disengaged interposed in said 35 power-driven means, a revolute member impelled by said power-driven means and having a definite speed of rotation with reference to that of said turret, means actuated by the movement of said slide for engaging said clutch, means carried by said revolute member for retaining said clutch in engagement for a determined period independent of the position of the slide, and means independent of the slide for disengaging said clutch.

16. The combination of a bed, a slide, a 50 turret on said slide, driving means for said turret, including gearing carried by the bed, and means acting upon a member of said gearing to lock said turret.

17. The combination of a bed, a slide, a 55 turret on said slide, driving mechanism for the turret, including gearing carried by the bed, a device for controlling rotation of the turret applied to a portion of said gearing, and means actuated by motion of said slide 60 and coacting with said device for locking and unlocking the turret and for imparting rotative motion thereto through said gearing.

18. The combination of a bed, a slide, a 65 turret on said slide, a stop-block on the bed, a movable member on said stop-block, driving means for said turret, including gearing carried on the bed, locking means acting through said gearing to normally hold said turret stationary with relation to said slide, additional 70 locking means intermediate said slide and said turret, means acting on contact with a member of said stop-block to release said additional locking means, and means acting on contact with the movable member on said 75 block to release said locking means first mentioned.

19. The combination of a bed, a slide, a turret on said slide, driving means for said 80 turret, including gearing carried on the bed, a clutch interposed in said turret-driving means, a turret-stop member carried by a member of said gearing, turret-stop means carried on the slide, a stop-block adjustably mounted on the bed, clutch-operating means, 85 a movable member on said block, connection between said movable member and said clutch-operating means, a member on said slide adapted to engage said movable member on said block, and an actuating-arm connected with the turret-stop means carried on the slide, and arranged to contact with said block.

CARL J. FORSBERG.
